UNITED STATES PATENT OFFICE.

ELDREDGE M. MURRAY, OF CHICAGO, ILLINOIS.

DESIGN FOR A CAP FOR AUTOMOBILE RADIATORS.

Application filed June 6, 1923. Serial No. 6,427. Term of patent 3½ years.

To all whom it may concern:

Be it known that I, ELDREDGE M. MURRAY, a citizen of the United States, residing at Chicago, in the county of Cook and State of Illinois, have invented a new, original, and ornamental Design for Caps for Automobile Radiators, of which the following is a specification, reference being had to the accompanying drawings, forming part thereof.

Fig. 1 is a front elevation of a radiator cap embodying my new and improved design;

Fig. 2 is a top plan view of the structure illustrated in Fig. 1.

I claim:

The ornamental design for a cap for automobile radiators as shown.

ELDREDGE M. MURRAY.
